UNITED STATES PATENT OFFICE

DONALD E. RUTISHAUSER, OF ST. LOUIS, MISSOURI, ASSIGNOR TO HUSSMANN-
LIGONIER COMPANY, OF ST. LOUIS, MISSOURI, A CORPORATION OF DELAWARE

REFRIGERATED CASE

Application filed November 28, 1930. Serial No. 496,706.

This invention relates generally to improvements in refrigerated cases, and particularly to an improved refrigerated case which includes a display compartment and a bulk storage compartment, the predominant object of the invention being to provide a case of this type which is provided with a refrigerated partition for separating the display and bulk storage compartments.

10 Another object of the invention is to produce a refrigerated case of the type referred to above which includes a common door giving access to both the display compartment and the bulk storage compartment, the structure including also a secondary door, operable through the door opening closed by the common door referred to, which isolates the display compartment from the bulk storage compartment when access is being had to the bulk storage compartment through the opening of the common door.

Still another object of the invention is to provide improved refrigerating units for refrigerated cases which are so constructed that the outer surfaces thereof are substantially flat, whereby frost may be removed from said units by the simple operation of brushing the flat surfaces thereof with a stiff brush, instead of defrosting in the common manner involving discontinuing operation of the refrigerating units until the frost has melted therefrom.

The invention includes other important objects which will be apparent after careful consideration of this application and the drawings forming a part thereof, in which

Fig. 1 is a vertical section taken through the improved refrigerated case;

Fig. 2 is a vertical section taken on the line 2-2 of Fig. 1; and

Fig. 3 is a fragmentary front elevation on a reduced scale of the case illustrated in Figs. 1 and 2.

In the drawings, wherein is shown for the purpose of illustration, merely, one embodiment of the invention, A designates the improved refrigerated case as a whole, said case being provided with the usual insulated bottom, top, front, back, and end walls common to structures of this type. The front

wall includes as a part thereof an inclined portion B, which is comprised of a plurality of spaced layers C of glass or other suitable transparent material.

The interior of the case A is divided by a partition 1 into a display compartment D and a bulk storage compartment S, said partition preferably being inclined downwardly from the back of the case to the front thereof, as shown most clearly in Fig. 1. The partition 1 comprises a hollow structure having flat top, bottom, side, and end wall surfaces, said hollow structure preferably being formed of sheet metal or other suitable material. Arranged within the hollow structure providing the partition 1 is a conductor 2 which provides a conduit for a refrigerant. The conductor 2 is arranged tortuously within the partition 1 so that the entire partition is subject to the refrigerating effect of the refrigerant passing through said conductor, and the opposite end portions of said conductors extend through wall portions of the partitions and are connected to other conductors (not shown) which conduct the refrigerant to the conductor 2. The hollow structure which provides the partition 1 is fluid-tight and a suitable heat-transmitting medium is located within said hollow structure. The heat-transmitting medium may be in the form of a fluid, as suggested at 2' in Fig. 1, or, if desired, said medium may be in the form of a suitable material which is poured into the hollow structure 1 and hardens therein to provide a solid mass. Also, a suitable gas may be employed within the hollow structure 1 as a heat-transmitting medium.

The function of the heat-transmitting medium is to conduct heat from the outer surfaces of the hollow structure inwardly to the conductor 2, where said heat is dissipated. The heat-transmitting medium substantially fills the hollow structure, the conductor 2 being submerged or embedded therein, as the case may be, and said medium is characterized by the ability to retain low temperature for a considerable period after the refrigerating means of the case has been discontinued.

The partition 1 is supported by supporting

elements 3 and 4 which extend longitudinally of the interior of the case A, said elements being secured to suitable brackets 5 and 6 fixed to the front and rear walls, respectively, of the case. The element 3 preferably is in the form of an elongated angle bar arranged as shown in Fig. 1; that is to say, the arrangement of the angle bar is such that portions of the end and bottom walls of the partition contact with the legs of the angle bar so that said partition is maintained in its inclined arrangement without the need for fastening devices. The supporting element 4 is preferably in the form of a flat bar 10 on which the upper end portion of the partition rests.

Supported by the partition 1 at the top surface thereof is a plurality of trays 8 for the foodstuffs which may be displayed within the display compartment D of the case A. Each of the trays 8 comprises a flat wall portion 9, at the forward or lower end of which an angularly extended, upwardly projected foot 10 is arranged. Each tray 8 at its opposite side edges is provided with down-turned flanges 11 (Fig. 2), which rest upon the top surface of the partition in a manner to cause wall portion 9 to be spaced apart from the top surface of the partition, where-by a passageway 12 for air is provided which is open at its forward and rearward ends. The trays 8 are maintained in place on the partition by spaced apart clips 13 which are secured to the trays and engage the rear end 30 wall of the partition, as shown in Fig. 1. Preferably I employ a plurality of the trays 8 arranged end to end with respect to each other, as shown in Fig. 2, but it is obvious that I may employ a single tray if desired.

Secured to the inner face of the front wall of the case A is a strip of material 14 (Fig. 1) which throttles or controls the passage of air from the display compartment D to the bulk storage compartment S through the space 7 between the forward wall of the partition 1 and the front wall of the case A, this strip being fixed to said front wall of the case and overlying the forward portion of the top wall of the partition. The strip of material 14 extends longitudinally of the case A from end to end thereof and is provided with a plurality of apertures 14' formed therethrough. I also employ a strip of material 15 which is fixed to the front wall of the case above the strip 14. The strip of material 15 is so shaped that it extends inwardly and downwardly from the front wall of the case, said strip having a portion 16 which is arranged parallel with and in spaced relation with respect to the foot portions 10 of trays 8, so as to provide a space 17 for the passage of air between said foot portions and said strip portion 16. The strip of material 15, like the strip 14, extends longitudinally of the 60 interior of the case A from end to end there-

of. At the rear end of the partition 1 I employ a substantially triangular shaped element 18 which extends longitudinally of the interior of the case. This element serves to approximately close the space at the rear end 70 of the partition 1 so that circulation of air within the interior of the case A may be controlled to better advantage.

In the upper portion of the display compartment D of the case A I provide a refrigerating unit 19, which comprises a plurality of hollow structures 20 constructed in accordance with the construction of the partition 1; that is to say, each hollow structure 20 is preferably formed of sheet metal 80 in a manner to provide a substantially fluid-tight structure. The hollow structures 20 are spaced apart from each other so as to provide spaces or passageways 20' between adjacent hollow structures and preferably said hollow structures extend longitudinally of the case from end to end thereof, as shown in Fig. 2.

The refrigerating unit 19 is supported in place by a supporting structure which includes a plurality of spaced elements 21, the opposite end portions of each of which are secured to the front and rear walls, respectively, of the case A. Also, the supporting structure for the refrigerating unit 19 includes a plurality of members 22, one of which is arranged beneath each element 21. Each of the members 22 is shaped to provide depressions 23, in which the lower end portions of the hollow structures 20 are seated, and the members 22 and elements 21 are connected together by bolts 24 which extend vertically through the spaces 20' between adjacent hollow structures 20. Each of the hollow structures 20 has disposed therein a tortuously arranged conductor 25 through which a refrigerant is passed, and, as in the case of the partition 1, the hollow interior of each hollow structure contains a suitable heat-transmitting medium 25'. The conductors 100 25 in the various hollow structures 20 are connected together, and preferably the conductors 25 are arranged in direct communication with the conductor 2 within the partition 1.

26 designates a baffle which is disposed as shown in Fig. 1. This baffle extends longitudinally of the interior of the case A and preferably comprises a layer of insulating material 27 which is covered by sheet metal 120 or other suitable material 28. The baffle 26 is suspended by spaced hangers 29 from angle elements 30 fixed to the front wall of the case, and its function, as will presently appear, is to assist in controlling the circulation of air within the display compartment of the case A.

Arranged within the bulk storage compartment S of the case A is a refrigerating unit 31 which is constructed in the manner of the 130

partition 1 and the hollow structures 20 of refrigerating unit 19; that is to say, the refrigerating unit 31 includes a hollow structure 32 in which tortuously arranged conductor 33 for a refrigerant is disposed. The hollow structure 32 is supported by a supporting element 34, and the interior of said hollow structure contains a heat-transmitting medium 38 in which the conductor 33 is submerged. The refrigerating unit 31 extends longitudinally of the interior of the bulk storage compartment of the case A and preferably the conductor 33 thereof is in direct communication with the conductors 2 and 25 of the partition 1 and refrigerating unit 19, respectively.

In the rear wall of the case A I provide one or more door openings 35 which are closed by one or more doors 36 of the usual insulated construction and arrangement. The door opening 35, when one door is employed, or each door opening when the case is provided with a plurality of doors in its rear wall, gives access to both the bulk storage compartment S and the display compartment D; that is to say, my improved case is not provided at its rear wall with separate doors for the bulk storage compartment and the display compartment. The door or doors 36 may be of the hinged or sliding type as desired, and said door or doors are of such height that free access may be had to the compartments above and beneath the partition 1.

Arranged immediately inside the door or doors 36 is one or more secondary doors 37, which close the rear portion of the display compartment D of the case A. The secondary door 37, or each of such doors when more than one is employed, is mounted for vertically sliding movement by having its opposite end portions arranged in guideways 38 formed in vertically disposed elements 39 located at the opposite ends of the door 37, or each of such doors, as the case may be. Each of the guideways is provided with a shoulder 40 (Fig. 1) at a point intermediate its upper and lower ends, and the guideway above said shoulder tapers from a narrow width at the top of the guideway to a wider width at the shoulder. When the secondary door is in the position where it closes the rear end of the display compartment D the lower ends of the side portions of the door, which are arranged in the guideways 38, rest on the shoulders 40. This arrangement results in the secondary door being maintained in its elevated position, as shown in Fig. 1. When, however, it is desired to remove the secondary door from its elevated position, as when it is desired to gain access to the display compartment D, the knob 41 on the secondary door is grasped and the lower portion of said secondary door is moved rearwardly so as to remove the lower portion of the secondary door from the shoulders 40. The

secondary door may then be moved downwardly to the portions of the guideways 38 located beneath the shoulders, whereby the display compartment will be free from obstruction at its rear end and the secondary door will be disposed at the rear of the bulk storage compartment of the case A.

Arranged longitudinally of the interior of the bulk storage compartment S is a pair of trackways 42 which are supported by the front and rear walls of the case A. The trackways 42 support a plurality of trays 43 for sliding movement longitudinally of the bulk storage compartment S, said trays being provided with suitably arranged rollers 44 which rest upon the trackways 42. As shown in Fig. 3, the longitudinal space of the bulk storage compartment S occupied by the trays 43 is substantially less than the entire longitudinal space of said compartment, hence it is possible to shift the trays longitudinally of the bulk storage compartment so as to permit free access to the lower portion of said compartment. The trays 43 are intended to receive foodstuffs for which there is a demand at all times, but when slower moving foodstuffs contained in the lower portion of the bulk storage compartment are desired, it is necessary merely to shift the trays so that access may be had to the desired articles.

In the use of my improved refrigerated case the refrigerated partition 1, which separates the display compartment and the bulk storage compartment, provides an efficient refrigerating unit for both of said compartments, and while I employ also the refrigerating units 19 and 31 in addition to the refrigerated partition, these latter refrigerating units are not absolutely essential and in many cases may be dispensed with. During operation of the case illustrated in Fig. 1, air is circulated through the display compartment and through the bulk storage compartment in a manner which is perfectly obvious, the circulation of air in the display compartment being such that the warmer air passes upwardly along the front of said compartment and moves over the upper edge of the baffle 26 to the top of the refrigerating unit 19, whence said air passes downwardly through the passageways 20, where its temperature is substantially reduced. The function of the secondary door 37 is to prevent warm air from rushing into the display compartment, when the door 36 is opened to gain access to the bulk storage compartment, and fogging the inner face of the transparent portion C of the front wall of the case, as said secondary door acts as a baffle which prevents such inrush of warm air. Also, the strip of material 15 prevents warm air, which enters the bulk storage compartment when the door 36 is opened, from being forced upwardly through the space 7 when the door is moved to its closed

position. This feature of the invention is important as such warm air would move against the inner face of the transparent portion of the front wall and fog the same. The passageways 12 and 17 provide a passageway for the circulating air within the display compartment, which causes some of said air to pass along a path where the trays 8 are subjected to maximum refrigerating efficiency of said air. The purpose of the element 18 is to prevent air within the display compartment from freely moving downwardly into the bulk storage compartment. The strip of material 14 serves to control the passage of air from the display compartment to the bulk storage compartment, as this strip of material is provided with apertures in such number as to permit just the desired amount of air to pass from said display compartment to said bulk storage compartment. In other words, if the use of the case be such that it is necessary to permit a substantial amount of cold air to pass from the display compartment to the bulk storage compartment, a greater number of apertures will be provided in the strip 14 than would be the case if less cold air were required to pass from the display compartment to the bulk storage compartment. In this manner the passage of cold air from the display compartment to the bulk storage compartment is absolutely controlled. When desired the strip 14 may be imperforate so as to prevent any passage of air from the display compartment to the bulk storage compartment.

An important feature of the invention resides in the fact that all of the refrigerating units, that is, the partition 1 and the refrigerating units 19 and 31, are provided with substantially flat outer surfaces capable of being brushed with a brush having stiff bristles for the purpose of removing frost therefrom. This entirely eliminates the necessity for discontinuing the operation of the refrigerating units of the case for the purpose of defrosting, as heretofore.

I claim:

1. A refrigerated case comprising a display compartment and a bulk storage compartment, a partition separating said compartments from each other, a door through which access may be had to both of said compartments, a secondary door arranged to close said display compartment when access is being had to said bulk storage compartment, and means for supporting said door for sliding movement.

2. A refrigerated case comprising a display compartment and a bulk storage compartment, a partition separating said compartments from each other, a common door through which access may be had to both of said compartments, and a secondary door arranged to close said display compartment when access is being had to said bulk storage

compartment, said secondary door being movable from a position where it closes the display compartment to a position where it substantially closes the bulk storage compartment.

3. A refrigerated case comprising a display compartment and a bulk storage compartment, a refrigerated partition separating said compartments from each other, and a supporting medium for articles displayed within said display compartment, said supporting medium being supported by said refrigerated partition and being maintained in spaced relation with respect thereto to provide a passageway between said partition and said supporting medium for circulating air within the display compartment.

4. A refrigerated case comprising a display compartment having a transparent wall portion and a bulk storage compartment, a partition separating said compartments, a common door for giving access to both of said compartments, and baffle means for preventing passage of air from said bulk storage compartment to a point within said display compartment adjacent to the location of the transparent wall portion thereof when said door is operated.

In testimony that I claim the foregoing I hereunto affix my signature.

DONALD E. RUTISHAUSER.
